(57) **CLAIM**

The ornamental design for a display assembly, as shown and
described.

DESCRIPTION

FIG. 1 is a front, perspective view of a display assembly
showing our new design;

FIG. 2 is a rear, perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and

FIG. 8 is a bottom view.

FIG. 9 is a front, perspective view of the display assembly of
FIG. 1 with portions of the unclaimed subject matter removed
and the remaining portion of the display assembly shown in a
larger scale;

FIG. 10 is a rear, perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and

FIG. 16 is a bottom view.

FIG. 17 is a front, perspective view of the display assembly of
FIG. 1 shown with additional unclaimed environmental sub-
ject matter;

FIG. 18 is a front view thereof;

FIG. 19 is a right side view thereof;

FIG. 20 is a left side view thereof;

FIG. 21 is a top view thereof; and,

FIG. 22 is a bottom view.

The features shown in broken lines are portions of the display
assembly or environmental subject matter to the display
assembly forming no part of the claimed design. The features
shown in long dash-short dash broken lines indicate bound-
aries of the claimed design and form no part of the claimed
design.
